UNITED STATES PATENT OFFICE.

ROBERT PILSON, OF LAUREL, MARYLAND.

IMPROVEMENT IN MACHINES FOR PREPARING COTTON FOR CARDING-ENGINES.

Specification forming part of Letters Patent No. 59,259, dated October 30, 1866.

To all whom it may concern:

Be it known that I, ROBERT PILSON, of Laurel, Prince George county, and State of Maryland, have invented a new and useful machine to be used for preparing cotton and other fibrous material for the cards, and which I call a "Graduated Lap-Frame," and I do hereby declare that the following is a full, clear, and exact description of the construction and operation of the same, reference being had to the annexed drawings, making a part of this specification, in which—

Figure 1 is a ground plan, and Fig. 2 is a longitudinal sectional view.

The object of the invention is to prepare the cotton in a superior manner for the card by separating, without injuring the fiber, the material from dirt, dust, and all foreign substances, and enabling the manufacturer to use inferior and dirty cotton, and producing therefrom manufactured fabric equal to that produced from first-grade material, and also saving a large proportion of both labor and wear of machinery, particularly of the cards.

The graduated lap-frame consists of a table (marked A) hinged to the end of the machine, and on which the cotton is spread and presented to the nip of the feeding and drawing rollers, three of which (marked B) are fluted in any suitable manner, and one, B¹, smooth, the set nearest the cylinder D turning at an increased velocity, so as to produce a drawing action on the material. Under the smooth roller B¹, in front of the cylinder, is placed a steel protecting-knife, (marked C,) which may be so attached to the frame that it may be adjusted as the knife wears away. This knife is to prevent the cotton from clogging or lapsing on the rollers, the cotton passing from the rollers to a rapidly-revolving cylinder, (marked D,) which I call the "first cleaning-cylinder," and in which are placed cylindrical tapering metal teeth. This cylinder receives the cotton from the rollers, disentangles and opens up the fiber, and throws it on the previous cylinder, (marked E,) through which the dust from the fiber falls or is drawn in any suitable manner. Above this cylinder, and nearly in contact therewith, I place a compressing-roller, (marked I,) which condenses the loose fiber on this cylinder in the form of a bat, and presents it to the next pair of feed-

ing and drawing rollers, from which the material is drawn by the second cleaning-cylinder, D¹, which is provided with teeth finer and more thickly set than those of cylinder D. The fiber, being thus partially cleaned, is still further distended or drawn out, the finer teeth drawing together and laying the fiber nearer in parallel lines, which is of very great advantage, each combing action still further cleaning and distending, and finally presents the fiber in proper condition for the card. This cylinder D¹ deposits its loose fiber into the apartment marked J, provided with a suitable exhaust for the dust and finer particles. In this apartment are placed two pervious cylinders, E¹ and E², and a deflector, F. This deflector is also pervious, and is placed at the side of the cylinder E², and prevents the loose fibrous material from passing with the dust out through the exhaust G, and the opened fiber thrown on the surface of the pervious cylinders E¹ and E² is fed through between the same; and by this arrangement of an exhaust above and a pervious cylinder below, acting in the same manner as the cylinder E, previously described, I am enabled more thoroughly to remove the dust from the floating mass.

The material passing between the pervious cylinders E¹ and E² is partially condensed, and is then still further condensed in passing through between the cylinder E¹ and roller I¹. The roller I¹ also performs the functions of a doffer for the upper cylinder, E². This second condensed lap is again presented to the next set of feeding and drawing rollers, and then to a third cylinder, D², provided with teeth still finer and more thickly set than those of cylinder D¹, and which gives a finer combing action, and deposits its fiber on cylinders E³ and E⁴ in an apartment, J¹, provided with a pervious deflector, F¹, and an exhaust acting in every particular as those already described in the apartment J.

The bat, when compressed between the cylinder E³ and roller I², is delivered between condensing-rollers K, the upper ones of which are held in movable bearings, and resting on which at each side are the levers L, provided with suitable springs and nuts, to adjust the pressure as desired. From between these rollers the lap firmly compressed passes to and

is wound round a tapering roller, H. This roller is made of metal, and is tapered from one end toward the other to better facilitate its removal from the lap, and the lap is then ready for the carding operation.

Each cylinder D D¹ D² may be rotated at the same or at increasing velocities. The drawing-rollers may be connected by a suitable gearing to give a greater or less drawing action, and each lower smooth roller may be provided with an adjustable knife-edged cleaner.

Above the machine, and connected with the apartments J J¹, is situated the exhausting-pipe G, through which escapes all dust and light substances, and the same is driven out at the top of said pipe, which is open, by the current of air set in motion by the rapid revolution of the several cylinders.

What I claim, and desire to secure by Letters Patent, is—

1. The combination of two or more sets of drawing-rollers with two or more toothed cylinders, when the rollers and cylinders are arranged in the order described, and the teeth of the second and each succeeding cylinder are finer and more thickly set than those of the cylinder immediately preceding it.

2. The combination of two or more sets of drawing-rollers and two or more toothed cylinders, the teeth of the second and each succeeding cylinder being finer and more thickly set than those of the cylinder immediately preceding it, with two or more previous cylinders

through which dust and other impurities may pass, and between the surface of which and a suitable roller the opened fibrous material, as delivered from each toothed cylinder, passes, and is partially condensed before it is presented to the action of the next cylinder.

3. The combination, in a suitable case or apartment, of the previous cylinders E¹ E² and deflector F, when the said apartment is provided with an exhaust arranged in respect to the said rollers and deflector substantially as shown and described.

4. The combination of the previous rollers E¹ E² and fluted roller I¹, the three operating to condense the loose fibrous material as received from a toothed cylinder, and the roller I¹ so arranged in relation to the roller E² as to act as a doffer for that roller.

5. The combination of the fluted drawing-rollers B, smooth roller B¹, cleaning knife or bar C, and toothed cylinder D, substantially as and for the purpose described.

6. The tapering lap-roller H, as and for the purpose described.

7. The combination and arrangement of the several devices, as a whole, herein described, and constructed and operating to draw, open, clean, condense, and wind into a lap cotton or other fibrous material ready for the carding-machine.

ROBERT PILSON.
